UNITED STATES PATENT OFFICE

ERIC SODERGREN, OF SIERRA MADRE, CALIFORNIA

REGULATOR FOR WINDOWS AND DOORS

Application filed July 26, 1927. Serial No. 208,623.

My invention relates to door and window regulating devices of the general character embodied in my co-pending application filed July 16, 1927, Serial No. 206,244, and involving means by which a window or door can be firmly held in closed and open positions against movement under the action of wind, yet permitting manual adjustment of the window or door at will.

It is a purpose of my present invention to provide a highly efficient and substantial regulating device particularly adapted, although not necessarily for use with outwardly opening casement windows having inside screens, my device being associated with the windows in such manner that the latter can be readily moved at will to open and closed positions from a point within the room, and all without removing or in any way disturbing the window screen, to the end that the latter can remain in place in the window frame at all times and yet the window conveniently adjusted as desired.

I will describe only two forms of regulators for windows and doors embodying my invention and will then point out the novel features in claims.

In the accompanying drawings:

Figure 1 is a fragmentary view showing in side elevation one form of regulating device embodying my invention in applied position to an outwardly opening casement window;

Figure 2 is a sectional view taken on the lines 2-2 of Figure 1 and looking in the direction of the arrows;

Figure 3 is a sectional view taken on the lines 3-3 of Figure 1 and looking in the direction of the arrows;

Figure 4 is an enlarged detail sectional view taken on the lines 4-4 of Figure 1 and looking in the direction of the arrows;

Figure 5 is a vertical sectional view of a holding element embodied in my invention and also illustrated in Figure 4;

Figures 6 and 7 are views similar to Figures 1 and 2 respectively and illustrating a second form of regulating device embodied in my invention;

Figure 8 is an enlarged sectional view

taken on the lines 8-8 of Figure 6 and looking in the direction of the arrows, and

Figure 9 is a fragmentary bottom plan view of the mechanism illustrated in Figure 8.

Referring specifically to the drawings in which similar reference characters designate similar parts in each of the several views, my invention in its two embodiments illustrated is particularly adapted for use in connection with an outwardly opening casement window W mounted to swing on hinges 10 secured to a window frame F in which latter a screen S is mounted at its inner side to completely span the window opening in the frame.

To provide means by which the window W can be adjusted without removing or in any way disturbing the screen S, I provide a regulating device constituting an actuating mechanism which in the embodiment shown in Figures 1 to 5 inclusive comprises a rotary element in the form of a shaft 11 rotatably mounted in a vertically disposed sleeve 12 tightly fitted in an opening in the stool 13 of the window frame F at a point adjacent to the hinge side of the window W. The shaft 11 projects above the stool 13 and is provided with a collar 14 for preventing downward displacement of the shaft in the sleeve 12, while the extreme upper end of the shaft is squared as indicated at 15 and is received in a squared pocket 16 formed in the hub portion 17 of an arm A, the arm being secured against displacement from the shaft by means of a washer 19 and a screw 20 extending through the washer and hub portion 17 and threaded into the end of the shaft. An L shaped bracket B is secured to the inner side of the window W by means of screws 21 and is provided with an opening 22 through which the arm A in the form of a round rod, freely extends and is disposed substantially parallel to the window when the latter is closed. It will be clear that

upon rotation of the shaft 11 the arm A will have sliding engagement with the bracket B to cause the window W to be swung to open or closed position according as the shaft is rotated in one direction or the other.

The shaft 11 also projects below the stool 13 and its lower end is provided with a head 23 having an opening therethrough in which is received a sleeve 24 forming one part of an extensible member M, the sleeve being secured to the head by means of a set screw 25 having a lock nut 26. The other part of the member M is in the form of a rod 27, telescopically associated with the sleeve and provided with a reduced flattened end 28 projecting through registering slots 29 and 30 formed respectively in the apron 31 of the window frame W and a finishing plate 32 secured to the apron.

15 The reduced end 28 of the rod 27 is pivotally connected to a holding element designated generally at H by means of a pin 33 extending through registering openings in the rod and in a pair of spaced ears 33^a formed on the holding element.

20 The holding element is in the form of a rectangular flat body 34 which is slidably mounted on a guide bar or track 35 extending through a slot 36 in the body, the latter being supported in a horizontal position in parallel spaced relation to the apron 31 by means of brackets 37 secured to the bar at its ends by means of screws 38 and to the apron by screws 39.

25 In order to set up friction to resist movement of the holding element on the bar 35, a shoe 40 is extended through the slot 36 at the lower side of the bar and is urged into engagement with the bar by means of a coil spring 41 seating in a pocket 42 in the body 34 and bearing against a washer 42^a while a wear plate 43 is extended through the slot 36 at the other side of the bar so that the latter is interposed between the shoe and wear plate.

30 Longitudinal displacement of the shoe and plate is prevented by means of laterally extending lips 44 and 45 on the ends of the shoe and plate respectively.

35 To provide means for locking the holding element against movement on the bar 35 a locking screw 36^a is threaded into the underside of the body 34 and extends through the pocket 42 for engagement with the washer 42^a. The screw is provided with an operating handle 46, and for limiting the unlocking movement of the screw the body 34 is provided with a projection 47 disposed in the path of the handle, while to prevent accidental rotational movement of the screw a coiled expandible spring 48 is interposed between the body and handle in surrounding relation to the screw.

40 In the operation of this form of my invention it will be clear that upon grasping the holding element at its opposite sides, which are concave as indicated at 49 to facilitate grasping thereof, and then sliding the element along the bar, the extensible member M will be moved to rotate the shaft 11, and through the medium of the arm A and bracket

B effect swinging movement of the window W upon its hinges 10. The window can thus be adjusted from the inner side of the screen S without removing the latter, and will be frictionally held in the position to which it is adjusted, against movement under the action of wind, by means of the friction set up against the bar 35 by the shoe 40, yet can be manually moved when sufficient pressure is exerted against the holding element to overcome the frictional resistance set up by the shoe.

45 In the form of my invention shown in Figures 6 to 9 inclusive the shaft 11^a carrying the arm A engaging the bracket B, is journaled in a rectangular shaped frame 50 extending through an opening 51 formed in the stool 13 and secured to a plate 52, which latter is in turn secured to the stool by screws 53 so as to support the frame beneath the stool.

50 Secured to the shaft 11^a are a pair of spaced arms 54 having slots 55 in which are received pins 56 extending in opposed directions from a feed nut 57 threadedly engaging a threaded feed shaft 58 journaled in the frame for rotation about a horizontal axis and extending outwardly from the frame through the apron 31 where it is provided with an operating handle 59. Longitudinal displacement of the feed shaft 58 is prevented by a collar 60 secured to the shaft and interposed between a clip 61 and one side wall of the frame 50, while the feed nut 57 is restricted to movement longitudinally of the shaft 58 when the latter is rotated, by means of one of the pins 56 which is extended to travel in a slot 62 formed in the under side of the frame 50.

55 In the operation of this form of my invention, it will be clear that rotation of the feed shaft 58 by means of the handle 59 will cause the nut 57 to be fed longitudinally of the shaft thus rotating the shaft 11^a through the medium of the arms 54 and effecting swinging movement of the window W about its hinges 10.

60 Due to the fact that the nut 57 cannot drive the feed shaft 58 but can only be moved upon rotation of the shaft, the actuating mechanism is what is termed irreversible, so that the window will be positively locked in the position to which it is moved, against movement under the action of the wind.

65 Although I have herein shown and described only two forms of regulators for windows and doors embodying my invention, it is to be understood that various changes and modifications may be made therein without departing from the spirit of the invention and the spirit and scope of the appended claims.

70 I claim:

75 1. A regulating device of the character described comprising a shaft adapted to be vertically mounted for rotation about a fixed axis in the stool of a casement window frame,

an arm fixed to the shaft for rotation thereby, a bracket adapted to be secured to a casement window in the frame and with which the arm is slidably associated so that rotation of the shaft in one direction or the other will effect movement of the window to an open or closed position, and means operatively associated with the shaft for actuating the latter, said means comprising a guide bar adapted to be supported in horizontal fixed position upon the stool of the window frame, a holding element comprising a body slidably mounted on the bar, a shoe in the body normally urged into engagement with the bar to set up frictional resistance against movement of the body along the bar, a sleeve constituting an arm, secured to the shaft, and a rod pivotally secured to the body and extensibly associated with the sleeve.

2. A regulating device of the character described comprising rotary means adapted to be mounted for rotation about a vertical axis in the stool of a casement window frame, means by which the rotary means is adapted to be operatively connected to a casement window in the frame to open or close the window according as the rotary means is rotated in one direction or the other, means operatively connected to the rotary means for actuating the latter, the last means comprising a guide bar adapted to be supported in horizontal fixed position upon the stool of the window frame, a holding element comprising a body slidably mounted on the bar and having means for setting up frictional resistance to movement of the body along the bar, and an extensible operative connection between the holding element and rotary means through the medium of which rocking movement of the rotary means will be effected upon sliding movement of the holding element along the bar.

3. A regulating device of the character described comprising rotary means adapted to be mounted for rotation about a vertical axis in the stool of a casement window frame, means by which the rotary means is adapted to be operatively connected to a casement window in the frame to open or close the window according as the rotary means is rotated in one direction or the other, means operatively connected to the rotary means for actuating the latter, said actuating means comprising a fixed guide bar, a frictional holding element slidably mounted on the bar, and a linearly extensible operative connection between the holding element and rotary means.

4. A regulating device of the character described comprising a shaft adapted to be mounted for rotation about a fixed axis in the stool of a casement window frame, means by which the shaft is adapted to be operatively connected to a window in the frame for moving the window to open or closed position according as the shaft is rotated in one

direction or the other, and means for actuating the shaft comprising a fixed guide bar, a holding element slidably mounted on the bar, and a linearly extensible operative connection between the holding element and shaft.

5. A regulating device of the character described comprising rotary means adapted to be mounted for rotation about a vertical axis in the stool of a casement window frame, means by which the rotary means is adapted to be operatively connected to a casement window in the frame to open or close the window according as the rotary means is rotated in one direction or the other, means operatively connected to the rotary means for actuating the latter comprising a fixed guide bar, a holding element slidably mounted on the bar, and a pair of telescopically associated members, one of which is pivotally connected to the holding element and the other to the rotary means.

6. A regulating device of the character described comprising rotary means adapted to be mounted for rotation about a vertical axis in the stool of a casement window frame, means by which the rotary means is adapted to be operatively connected to a casement window in the frame to open or close the window according as the rotary means is rotated in one direction or the other, means operatively connected to the rotary means for actuating the latter comprising a fixed guide bar, a holding element slidably mounted on the bar, and a pair of members extensible linearly relative to each other, one of the members being pivotally connected to the holding element and the other to the rotary means.
